(57) **CLAIM**

The ornamental design for a foldable headset for use with virtual reality and augment reality systems, as shown and described.

DESCRIPTION

FIG. 1 is a perspective view of a virtual reality and augmented reality foldable headset in a folded configuration in

a bag below a CD case, wherein bag containing the headset and CD case are protruding out of a boxed container.

FIG. 2 is a front perspective view of the virtual reality and augmented reality foldable headset in a fully assembled configuration with a protective element on an edge of each temple section of the headset.

FIG. 3 is a rear perspective view of the virtual reality and augmented reality foldable headset in the fully assembled configuration with a protective element on an edge of each temple section of the headset.

FIG. 4 is a front view of the virtual reality and augmented reality foldable headset in the fully assembled configuration with a protective element on an edge of each temple section of the headset.

FIG. 5 is a rear view of the virtual reality and augmented reality foldable headset in the fully assembled configuration with a protective element on an edge of each temple section of the headset.

FIG. 6 is a side view of the virtual reality and augmented reality foldable headset in the fully assembled configuration with a protective element on an edge of each temple section of the headset.

FIG. 7 is a top view of the virtual reality and augmented reality foldable headset in the fully assembled configuration with a protective element on an edge of each temple section of the headset.

FIG. 8 is a side view of the virtual reality and augmented reality foldable headset in the fully assembled configuration with a protective element on an edge of each temple section of the headset.

FIG. 9 is a bottom view of the virtual reality and augmented reality foldable headset in the fully assembled configuration with a protective element on an edge of each temple section of the headset.

FIG. 10 is a front perspective view of the virtual reality and augmented reality foldable headset in the assembled configuration with a protective element on an edge of each temple section of the headset, and in the open configuration illustrating suction cups for holding a remote computing device; and,

FIG. 11 is a rear perspective view of the virtual reality and augmented reality foldable headset in the assembled configuration with a protective element on edge of each temple section of the headset, and in the open configuration illustrating suction cups for holding a remote computing device. The dashed broken lines in the Figures illustrate a remote computing device, such as a cell phone or portion thereof, and surface ornamentation and form no part of the claimed design.
